DESIGN FOR A ROBE

Ilsa Herdegen, New York, N. Y.

Application August 8, 1940, Serial No. 94,309

Term of patent 3½ years

To all whom it may concern:

Be it known that I, Ilsa Herdegen, a citizen of the United States of America, residing in New York city, county of New York and State of New York, have invented a new, original, and ornamental Design for a Robe, of which the following is a specification, reference being had to the accompanying drawing, forming part thereof, wherein,

The characteristic feature of my design resides in the series of concentric hearts arranged around the sleeves, and bottom of the robe, as shown.

I claim:

The ornamental design for a robe, substantially as shown and described.

ILSA HERDEGEN.
